[57] ABSTRACT

Machine for forming predetermined surfaces, such as toric surfaces on optical lenses. The machine is of a type in which the surfaces are determined by a base cam and by a transverse cam which is caused to move lengthwise of the base cam. The machine further has a frame, a first holder for a rotatable cup-shaped cutting tool, a second holder for the workpiece and coordinating mechanism for producing predetermined relative movement between said holders. The apparatus is particularly characterized in that the coordinating mechanism so controls the holders that the workpiece axis on the tool axis are always in the same plane or parallel planes and the relative movement between the holders comprises movement along axes which are positioned perpendicularly to one another. A device is provided for effecting automatic operation and for obtaining a wide range of adjustability to permit the manufacture of lenses having a wide range of contours, said latter including convex, concave and variable contours.

**MACHINE FOR PRODUCING SURFACES OF
OPTICAL LENSES, FOR EXAMPLE TORIC
SURFACES**

FIELD OF THE INVENTION

The invention relates to a machine for producing surfaces for optical lenses, particularly toric lens surfaces, wherein such surfaces are defined by a base cam and by a transverse cam which is moved along said base cam. It refers further to apparatus including a frame, a first holder for a rotatable cup-shaped cutting tool with a cutting lip which linearly contacts the workpiece, wherein the diameter of the tool and the sloped position of its axis relative to the base cam determines the form of the transverse cam particularly with respect to a nonrotatable workpiece. It also includes a second holder for the workpiece, particularly the rotatable cutting tool, and a coordinating mechanism for producing a predetermined relative movement between the first and second holder.

BACKGROUND OF THE INVENTION

In discussing the invention, the manufacture of toric lens surfaces should be considered to facilitate an understanding thereof, such manufacture of toric lens surfaces having great importance in the manufacture of eyeglasses. The invention is, however, not limited to machines with which toric lens surfaces can be manufactured inasmuch as the cams which are identified hereinafter as "base cam" and "cylinder cam" can also depart from a circular, or an approximately circular, shape.

A toric surface is created by the rotation of a circular arc at a certain distance around an axis which lies in the same plane as the circular arc. If the distance from the axis of rotation is larger than the circular arc radius, then a ring torus is created; if the distance is smaller, then a ton torus is created. In general toric surfaces of eyeglasses are parts of ring tori. The circle along which the producing circular arc of the torus is moved will be identified hereinafter as the base cam and the producing circular arc itself will be identified as the cylinder cam.

In manufacturing toric lens surfaces, cup-shaped tools are usually used, as illustrated schematically in FIGS. 1 and 2 of the drawings. The annular cutting lip *b* is brought into contact with the workpiece and is swung at a selected radius *R* about the workpiece. The radius which is thus produced on the workpiece is the above-mentioned base cam. For producing a cylinder cam having a selected curvature, the axis of rotation *c* of the cup-shaped tool *a* is adjusted in the plane of the base cam at a certain angle β to the line which connects the pivotal centerpoint *o* and the cutting lip point *p* which produces the base cam. During the production of the base cam the cylinder cam is produced simultaneously. The adjusting angle β for determining the cylinder cam depends on the diameter of the tool. In known machines positive (convex) and negative (concave) base cams are produced by changing the distance between the pivotal centerpoint *o* and the cutting lip *b*. In order to achieve an as large as possible positive and negative radius zone, the known machines must be provided with correspondingly long carriage guides which, to obtain the necessary rigidity for the machine, requires same to be made very heavy. The long carriage

guides and the great masses resulting therefrom require a horizontal arrangement of the plane of movement of the carriage. In general the limits for the radius of the base cam lie at ± 200 mm.

5 By using a cup-shaped tool, the cylinder cam, as stated above, is determined by the sloped position of the tool. The cylinder cam, therefore, frequently departs slightly from an exactly circular arc. However, the deviation is so small that it as a rule can be accepted.

10 The basic purpose of the invention is to construct a machine of the type mentioned above in such a manner that the radius of the base cam may be of any desired size, including infinite, with only a small size of machine.

15 This purpose is attained according to the invention by providing such coordinating mechanism, which consists of a control mechanism controlling one or both holders, that the workpiece axis and the tool axis remain always in the same plane or in parallel planes and the relative movement between the holders comprises a pivotal movement and a movement along axes which are positioned perpendicularly to one another.

20 In the machine of the invention the base cam is not directly passed through by the tool or workpiece. The same relative positions between tool and workpiece, as they exist in the known machines, are here achieved in such a manner that a selected sloped position of the tool axis relative to the workpiece axis is fixedly coordinated with a selected relative position of tool and workpiece in a rectangular coordinate system. In the inventive machine the movement which is carried out in known machines by a pivoted arm is divided into movements along rectangular coordinates and a sloped-position movement.

25 In this manner, a very compact design is obtained because only paths of movement of the size of the workpiece diameter are needed and a change of the base cam does not require any adjusting between tool and workpiece holder. The movements 30 can easily be so controlled that during stock removal the same relative movements between workpiece and tool are created, as would be created in the case of an as much as possible short or a very long, in a border case an infinitely long, swinging arm, as it would be

35 necessary in known machines. The movements can also be coordinated in such a manner that the base cam is neither a straight line (infinite radius) nor a circle (finite radius) but instead has any path, including a path which is variable and of interest in the manufacture of 40 special eyeglasses, for example eyeglasses with areas of different refractive power.

45 In a preferred embodiment of the invention, the first holder is movable relative to the machine frame along coordinates which are positioned rectangularly to one another and the second holder is pivotable about an axis which is arranged fixedly on the machine frame. This division of the movements results in a structurally 50 very simple machine and one in which the moving mechanisms for achieving the pivotal movement of the second holder can be arranged fixedly on the machine frame. This is possible because the pivotal axis is stationary relative to the machine frame.

BRIEF DESCRIPTION OF THE DRAWINGS

55 There are many possible embodiments for this machine. One exemplary embodiment of the invention is illustrated in the drawings, in which:

FIG. 1 illustrates three different relative positions between the concave side of an optical lens and a cup-shaped tool.

FIG. 2 is a corresponding illustration, wherein relative positions of a cup-shaped tool to a convex lens surface are illustrated.

FIG. 3 is a top view of a machine according to the invention.

FIG. 4 is a vertical cross-sectional view along the line IV—IV of FIG. 3,

FIG. 5 is a cross-sectional view along the line V—V of FIG. 3,

FIG. 6 illustrates a part of the machine,

FIG. 7 is a schematic illustration for explaining the operation of the machine during the manufacture of a concave lens surface and

FIG. 8 is an illustration corresponding to FIG. 7 for the manufacture of a convex lens surface.

DETAILED DESCRIPTION

The machine has a frame 60 (FIG. 3) on which are arranged a first holder which is collectively identified by the reference numeral 61 (FIG. 4) and a second holder which is collectively identified by the reference numeral 62. On the inside 63 of the housing-like frame there are arranged the control means for coordinating the movements of the first holder 61 and the second holder 62. In the illustrated exemplary embodiment, the first holder 61 is the workpiece holder and the second holder 62 is the tool holder.

The tool 1 is so arranged with respect to its annular cutting lip 2 that the centerpoint of the cutting lip radius coincides with the swivel axis 3 for the second holder 62. The tool 1 is secured on a tool spindle 4 which is clamped in a spindle head 5. The spindle head 5 is provided with a carriage guide 6 and can be laterally adjusted by means of a threaded spindle 7. This adjustability serves to adjust the machine to various diameters of the tool 1.

The spindle head 5 is connected to a pivotally mounted arm 8 through a carriage guide 6, said arm being secured on a shaft which is supported rotatably in the machine frame 60 (also called machine column). The axis of the shaft 9 corresponds to the mentioned pivotal or swivel axis 3. The tool spindle 4 is driven by a motor 11 (FIG. 5). The pivotal movement of the tool 1 is produced by means of a hydraulic piston 13 which has teeth 14 mating with a gear 12 secured on the shaft 9.

The workpiece 15 is adhesively fastened to a workpiece holder 16 which is secured on a liftable and lowerable rod 17 identified hereinafter as a quill. The quill 17 is provided with an annular piston 18 and is supported axially movably in a machine table 19 comprising a carriage. The quill 17 is secured against rotation by a guide rod 20. The axial movement is caused by hydraulic pressure fluid applied onto the annular piston 18.

The machine table 19 is guided movably alongside guideways 21 perpendicularly to the quill axis on the machine column 60. The machine table is moved by means of a hydraulic cylinder 23. In the illustrated exemplary embodiment, the transverse movement of the axis 22 of the quill and the swinging movement of the axis 64 of the tool spindle 4 both occur in a single plane. A conventional hydraulic power unit 24 supplies

the hydraulic pressure. The hydraulic lines are not illustrated.

A control cam 25 for producing the base cam is mounted on a holder 26 which is provided on the machine table 19. A scanning arm 27 which is guided in guide bearings scans the control cam 25. A guide arm 29 is provided on the scanning arm 27, which guide arm is aligned exactly parallel to the guideways 21 of the machine table 19. A feeler 31 is mounted on an arm 30 which is secured on the quill 17, which feeler has a scanning pin 32 which abuts under spring pressure the guide arm 29. The feeler 31 transmits during movement of the scanning pin 32 a positive or negative control voltage corresponding with the direction of movement. This voltage is amplified in an amplifier, not illustrated, and is fed to a hydraulic servo valve 33. Same controls the flow of hydraulic liquid to the cylinder 34 in which the annular piston 18 is movable so that the quill 17 is moved in the same direction as the scanning pin 32 and thereby returns the feeler 31 into its zero position.

A further control cam 35 for the swinging movement of the tool 1 is mounted on a holder 36 which is identical with the holder 26 for the control cam 25 provided on the machine table 19. A rocking lever 37 which is rotatably supported on a shaft 38 scans the control cam 35. An adjusting piece 39 for adjusting the angle β (see FIGS. 1 and 2) for selecting the cylinder cam is mounted on the rocking lever 37. The scanning pin 41 of a feeler 40 is pressed by spring pressure against the adjusting piece 39.

The feeler 40 is secured on an arm 42 which in turn is fixedly connected to the shaft 38. The shaft 38 is rotatably supported in bearings 43. A disk 44 is positioned fixed with respect to rotation of the shaft 38, on which disk a steel band is secured which loops around the disk 44 at a desired angle. The steel band 45 is secured with its other end on an equally large disk 46 and loops around same also at a selected angle. The disk 46 is connected fixedly with respect to rotation on and with respect to the shaft 9 to provide a mechanical connection through the steel band 45 between control cam 35 and tool 1 in such a manner that the sloped position of the tool, namely its swivel position with respect to the axis 3, is in a fixed relation to the position of the feeler 40 and therewith of the fixed control cam.

The steel band is held under tension by means of a weight 47. The weight 47 hangs on a rope 48 which is placed over a disk 44 which in turn is connected fixedly with respect to rotation of the shaft 38. The weight can also be replaced by a spring.

The feeler 40 is connected in the same manner as the feeler 31 to a servo valve 50 through a power amplifier. The servo valve 50 controls the flow of a hydraulic liquid to the hydraulic piston 13.

OPERATION

The machine operates as follows:

For selecting a certain base cam the associated control cam 25 is inserted into the holder 26. Also for the control of the swinging or rocking movement α (see FIGS. 1 and 2) a selected control cam 35 is mounted onto the holder 36. One particular control cam 25 is always associated with a given control cam 35. It is thereby advantageous (to avoid mix-ups) to combine both cams into one unit and so to select the arrangement of the feelers that the control cams can be ex-

changed as one unit. In the schematic illustration two separate control cams are illustrated for clarity.

To create a certain cylinder cam a corresponding adjusting piece 39 is inserted into the mounting of the rocking lever 37 and the adjusting angle β (FIGS. 1 and 2) is thereby adjusted.

For working of the lens surface (illustrated is the treatment of a convex lens surface), the workpiece 15 is brought into contact with the rotating tool 1 and the machine table 19 together with the workpiece 15 is moved by the hydraulic cylinder 23 into the swinging plane of the tool axis. The surface can be worked in one passage, namely during one movement of the machine table 19 from left to right (seen in FIG. 4), and the lens surface is completed.

During the movement of the machine table, the control cams 25 and 35 which are fixedly connected to the machine table 19, are moved relative to the scanning mechanisms. The scanning arm 27 and the rocking lever 37 are thus moved and move the scanning pins 32 and 41 of the feelers 31 and 40. Control signals in the form of positive or negative control voltages are thereby created. These signals are amplified through the power amplifiers and are fed to the servovalves 33 and 50.

The servovalve 33 controls the flow of hydraulic liquid into the hydraulic cylinder 34 and thus the movement of the quill 17 on which the workpiece 15 is provided. At the same time, the feeler 31 is moved in the same direction as the scanning pin 32. This enables the workpiece to carry out a movement which equals the contour of the control cam.

The servovalve 50 controls the flow of hydraulic liquid to the cylinder 65 in which the piston 13 is movable. Said piston acts through the teeth 14 to move the swinging arm 8 on which the tool 1 is mounted. Through the disks 44 and 46 and the steel band 45, the shaft 38 with the arm 42 and the feeler 40 is swung at the same angle as the scanning pin 41. The pivotal movement of the rocking lever 37 which is effected by the control cam 35 is thus transmitted onto the workpiece 1. By a suitable amplification of the signals in the power amplifiers the control deviation is kept sufficiently small that the manufacture tolerances are not exceeded. Very exacting control is possible because the movement of the feelers which cooperate with the control cams 25, 35 is relatively slow.

It is evident from an inspection of the drawings that by selecting suitable control cams 25 and 35 any desired connection between the movement of the workpiece and the swinging movement of the tool can be created. A control cam 25 with a straight line as a controlling contour corresponds with an infinite radius for the base cam. If then the cylinder cam is to have a constant value over the entire lens surface, the control cam 35 would also have a straight line as a controlling contour because the sloped position of the tool would remain unchanged during the passage of the workpiece. The base cam may have any desired form. The cylinder cam can also be changed during the grinding of a lens surface.

The operating principle of the aforescribed machine will be discussed again hereinafter in connection with FIG. 8.

The cup-shaped cutting tool a is moved during its operation so that its axis c carries out a swinging movement; the pivotal angle through which said tool acts

during one passage is identified with α . The workpiece does not carry out a rotation; however, it does provide lifting and lowering movements and a movement in horizontal direction is superposed onto these movements. At the start of a working cycle, the workpiece and tool have the relative positions with respect to one another which are illustrated with thin full lines. Later the workpiece is lowered and moves at the same time to the left. The tool is thereupon raised. After half of the passage is completed, the parts occupy the relative positions illustrated in thick full lines. During the further operation, the workpiece moves again upwardly, whereby the tool at the same time is again raised until finally at the end of the working the parts occupy the positions illustrated in dashed lines.

The manufacture of a concave surface occurs in an analogous manner which can be easily understood from FIG. 7 and therefore does not need to be explained further.

The invention has been discussed above in connection with one example in which control cams were used for the correlation of workpiece movement and tool movement. However, different embodiments will also fall within the scope of the invention. For example a digital control apparatus (see broken line illustration in FIG. 3) could be used which transmits coordinated impulses to a movement mechanism for the swinging movement of the one holder and the movement along coordinates the other holder. In place of hydraulic movement mechanisms, electrical movement mechanisms or combined mechanisms can also be used.

Although a particular preferred embodiment of the invention has been disclosed above for illustrative purposes, it will be understood that variations or modifications thereof which lie within the scope of the appended claims are fully contemplated.

I claim:

1. A grinding and polishing machine, comprising:
a frame;
guide means mounted on said frame;
first holder means comprising carriage means mounted on said guide means and adapted to move along a first path relative to said frame and quill means mounted on said carriage means for movement along a second path and in a direction perpendicular to the direction of said first path of movement of said carriage means, said first and second paths of movement defining a theoretical plane;
second holder means mounted on said frame for pivotal movement above a fixed pivot axis thereon;
cup-shaped tool means mounted on one of said quill means and said second holder means, said cup-shaped tool having a rim thereon;
workpiece holding means mounted on the other of said quill means and said second holder and adapted to hold a workpiece so that it will engage said rim of said cup-shaped tool means in response to a movement of said carriage means along said first path; and
control means for controlling the movement of said quill means and said second holder means and, consequently, said workpiece holding means and said cup-shaped tool in response to said movement of said carriage means along said first path.

2. A grinding and polishing machine according to claim 1, wherein said cup-shaped tool is mounted on

said second holder means and said workpiece holding means is mounted on said quill means.

3. A grinding and polishing machine according to claim 1, wherein said control means includes control cams and feelers adapted to engage said control cams.

4. A grinding and polishing machine according to claim 3, wherein said control means for controlling the pivoting movement of said second holder means includes an exchangeable adjusting piece which corresponds to a certain relative position between workpiece and tool.

5. A grinding and polishing machine according to claim 3, wherein said control means includes control cams for controlling said first and second holders, said control cams being connected to one of said carriage means and said frame.

6. A grinding and polishing machine according to claim 5, wherein said control means includes feeler means which cooperate with said control cams, said feeler means including signal generating means for transmitting signals to amplifiers which in turn act onto adjusting members for simultaneously adjusting the relative position between said tool means and said workpiece holding means.

7. A grinding and polishing machine according to claim 1, wherein said quill means includes a longitudinally movable rod which is guided in said carriage means and which is movable perpendicularly to the direction of movement of said carriage means.

8. A grinding and polishing machine according to

30

claim 7, wherein said control means includes control cams; and

wherein said control cams are mounted on said carriage means.

9. A grinding and polishing machine according to claim 7, wherein said rod has a piston thereon which is movable in an operating cylinder on said carriage means and is adapted to receive pressure medium on both sides thereof to control the movement thereof.

10. A grinding and polishing machine according to claim 7, wherein said second holder means is fixedly connected to a pivotal shaft which is supported on said frame; and

wherein said control means comprises a pair of relatively movable control cams and feelers, said feelers contacting said control cams and adapted to produce a signal in response to a movement of said feelers relative to said control cam, one of said feelers being coupled for controlling the swinging movement through a mechanical gearing to a pivotal shaft so that a rotary position of said pivotal shaft corresponds to a position of said one feeler.

11. A grinding and polishing machine according to claim 10, wherein said one feeler is fixedly connected to a feeler shaft and being rotatable therewith, a wind-up disk mounted on said feeler shaft and a band fixedly secured to and extending between said pivotal shaft and said wind-up disk.
